UNITED STATES PATENT OFFICE.

CHARLES STREIT, OF CINCINNATI, OHIO.

SOFA-BED.

SPECIFICATION forming part of Letters Patent No. 330,855, dated November 17, 1885.

Application filed July 27, 1885. Serial No. 172,841. (No model.)

To all whom it may concern:

Be it known that I, CHARLES STREIT, a citizen of the United States, and a resident of Cincinnati, in the county of Hamilton and State of Ohio, have invented certain new and useful Improvements in Sofa-Beds, of which the following is a specification.

This invention relates to folding lounges or sofa-beds, and especially to an improved means for uniting the stationary and folding frames, whereby they are more securely coupled together and readily folded or unfolded without liability of cutting or injuring the upholstering material.

My invention also includes certain peculiarities of construction and combinations of parts, whereby a cheaper, more comfortable, and durable article is produced, all of which will be first fully described in connection with the accompanying drawings, and particularly referred to in the claims.

Referring to the drawings, in which like parts are represented by similar reference-letters wherever they occur, Figure 1 is a front elevation of a folding lounge embodying my improvements. In this view a portion of the upholstering finish on the front is removed to expose the inner folded mattress. Fig. 2 is a vertical transverse section of the unfolded frames before being upholstered. In this view the lounge-back is removed, and the view is in the direction of the lounge-head. Fig. 3 is a rear elevation of my improved hinge for uniting the stationary and folding frames, represented in the position it assumes when the lounge is folded. Fig. 4 is a rear elevation of the central portion of the back rails of the stationary and folding frames, Fig. 1, with the back removed, showing my improved means for locking the frames together when folded. In this view the latch upon the folding frame is shown engaged with the detaining-hook on stationary frame. Fig. 5 is an enlarged elevation of the locking-latch secured to folding frame. In this view the latch is shown as drawn out of engagement with its hook. Fig. 6 is a vertical transverse section through line $\alpha\alpha$ of Fig. 4. Fig. 7 is an enlarged view in front elevation of my improved hinge in the position it occupies when the lounge is unfolded to form a bed. A portion of the rails of the two frames united by the hinge are shown in trans-

verse section as seen in Fig. 2. Fig. 8 is a top view of the hinge as shown in Fig. 7.

The stationary frame and folding frame are each composed of a back rail and end rails, of equal width, and a narrow front rail. The back rail of the stationary frame is indicated by A, and its end rails by A', and the narrow front rail by A². The back rail of the folding frame is indicated by B, and its end rails by B'. The front rail of the folding frame is indicated by B². Both frames are provided with cross-slats c, which are the supports for the upholstering-springs. These slats are let into grooves formed upon the inside of the longitudinal rails of both frames, and the top edges of the longitudinal rails A B and foot-rails A' B' are rabbeted at a b to furnish an offset, upon which the covering of the mattress is tacked down, thus avoiding the necessity for the upholstering-strips usually employed.

The cross-pieces b', in which the swinging pillow-supports D are journaled, provide the foundation for the mattress-cover at the head of the bed. The two frames when unfolded, as in Fig. 2, form substantially a spring-mattress box. The two together are upholstered precisely as though they were a single-mattress box. The same slats, c, that form the foundation for the bed-springs in frame B also serve for the seat-springs, which are placed upon the opposite sides of the slats. The front rails, A² and B², of both frames and the adjacent ends of the end rails, A' B', are united by the hinge represented in Figs. 3, 7, and 8. The hinge is composed of right and left members E, which are united together by the curved link F. Each of the members E have curved slots, which are concentric with the hinge-pivots e, and from the link F pins project into these slots and serve as stops to limit the play of the hinge members by coming against the ends of the slots, thus stopping the hinge in either the position shown in Fig. 1 or Fig. 2. The members E have feet e', turned at right angles to the upright portions. These are perforated to receive screws, which pass through them into the narrow front rails of the frames. The pieces E are also perforated with screw-holes, through which screws are passed into the end rails, thus securely holding the hinges in the angles formed by the front and end rails, and serving at the same

time to firmly brace the end and front rails together and support the hinge end of the folding frame when unfolded, as in Fig. 2. The pillow-supports D are round iron rods bent into an open rectangular frame. The short ends of the open side enter holes in the strips b', as shown in dotted line, Fig. 2, in which view the one upon the left is shown turned up as it is when the lounge is unfolded, to support the pillow, and the one upon the right-hand side is turned down, as both are when the lounge is folded. In the finished lounge these are covered with ticking, a single piece of which is doubled over both frames and stitched around them, so that both are united and move together, thus forming a continuous support across the head of the bed when turned up. When the frames are hinged together, the opening between the front rails of the lounge is covered with an upholstering fabric, g, in the prevailing fashion. When the lounge is unfolded, as seen in Figs. 2 and 7, this material folds under the arched link F without being injured or cut by the hinge, as is the case with the hinges now in common use.

The lounge is locked firmly in the closed position, Fig. 1, by my latch-fastening, Figs. 4, 5, and 6, which I will now describe. The latch H is a flat metal plate, which is pivoted to the outside of rail B by a screw, h. The plate H has projecting from it a ledge, h', which is perforated to receive a cord, I, Fig. 5, or strap I', Fig. 4, which extends above the seat, as seen in Fig. 1, by which the latch is released and the folding seat-frame turned over. The plate has also a hooked projection, h², to receive the free end of a coiled spring, J, which holds the lower hooked end of the latch in engagement with hook K, which is secured to the inside of rail A, and, extending above the edge of said rail, has its hooked end k projecting through a notch in the adjacent edge of the rail B. The spring J is secured to the rail B by its bent end and the staples j, j, between this end and the coil of the spring. The tapering notch in rail B guides the frames truly together, and, in connection with the hook k, prevents any end movement of the folding frame upon the stationary frame when locked, thus relieving the hinges from strain. The pins projecting from the link F through the concentric slot in the hinge members E, in addition to supporting the folding frame in either position,

also insure a steady movement when folding or unfolding the lounge, acting in this respect as a cog-gear, so that both ends of the lounge are bound to move together, and are not liable to drop suddenly or get in wind as when the plain three-leaf hinges are used. The legs b³, which support the outer edge of the frame when unfolded, are secured to the rail B in a position to come against the wood-work of the back M when the lounge is folded, as in Fig. 1, and they are finished to have the appearance of being a part of the back.

What I claim as new is—

1. A hinge for folding lounges, consisting of the right and left members E and arched coupling-link F, the said parts E having slots 70 concentric with the pivot-pins, and the link F having pins projecting from it to traverse said slots when the parts are pivoted together.

2. In a folding lounge, the combination of the stationary and folding frames, each composed of back and end rails of equal width, and the narrow front rails, A² and B², with the hinge composed of right and left members E, and arched link F, connecting the two members and bracing the front and end rails together, substantially as set forth.

3. The locking-latch for folding lounges, consisting of the hook-plate H, having perforation, as h, for the pivot-bearing, and having perforated ledge h' to receive cord or strap I and I', and spring J, the said latch being constructed to be secured to the back rail of a folding frame, and held in engagement with the hook or pin upon the stationary frame by the said spring J, and is also secured to the folding frame, substantially as shown and described.

4. The combination, substantially as specified, in a folding lounge, of the stationary frame A, A', and A² and the folding frame B, B', and B², hinged to the said stationary frame, as shown, with the latch H, h, h', and h², and the spring J, secured to the rail B of the folding frame, which has a notch in its meeting edge when folded, with a hook, K k, secured to the frame A and projecting above the edge of said frame and through the notch in frame B when the lounge is folded, substantially as shown and described.

CHARLES STREIT.
